ATTY.

UNITED STATES PATENT OFFICE.

HERBERT CECIL FINLAY, OF SYDNEY, NEW SOUTH WALES, AUSTRALIA.

ARTISAN'S INDIA-RUBBER GLOVE.

1,066,480.

Specification of Letters Patent.

Patented July 8, 1913.

Application filed August 24, 1911. Serial No. 645,784.

To all whom it may concern:

Be it known that I, HERBERT CECIL FINLAY, subject of the King of Great Britain and Ireland, residing at 75 York street, 5 Sydney, New South Wales, Australia, have invented new and useful Improvements in Artisans' India-Rubber Gloves, of which the following is a specification.

In certain trades and professions, the employment of india-rubber gloves is an imperative necessity; but such gloves have their drawbacks, especially if small articles have to be handled. These india-rubber gloves are merely digital sacks into which 10 the fingers of the operator can readily be introduced; consequently, the sense of touch, which is very delicate at the finger tips, is largely neutralized. This invention has been devised with a view to minimize, to 15 some extent, the disadvantages that are inseparable from the use of these gloves, and thus materially assist the operator in doing better work.

In giving effect to the invention, three 20 distinct improvements are made in india-rubber gloves: (a) the tips of the fingers of the gloves are made to fit the tips of the fingers of the hand within; (b) the tips of the index finger and thumb are provided 25 with artificial projecting finger nails; (c) the thumb side of the index finger is provided with undercut ribs, placed either longitudinally or transversely. The thumb 30 may be provided with two nails, one placed normally, the other over the fleshy inner 35 part of the thumb within the glove. But in order that the invention may be properly understood, reference is made to the accompanying sheet of drawings, in which:—

40 Figure 1 is a section of the index finger of an india-rubber glove with a human finger within. Fig. 2 is an external view of the same, showing the external longitudinal ribs. Fig. 3 shows an index finger and 45 thumb approached to one another, the index finger having transverse ribs. Fig. 4 is a cross section, on the line 1—2 of Fig. 2, showing the conformation of the ribs on the index finger. Fig. 5 shows how a small

article may be gripped between the index 50 finger and thumb of the glove.

A is a human finger inserted in the finger B of an india-rubber glove; the extreme end of the glove fingers are adapted to fit the tips of the human fingers within. The exterior of the glove finger is provided with a finger nail C over the place where the human nail is within the glove. The finger nail C will project from the end of the glove-finger and will be slightly undercut, as shown. 60 On the thumb side of the index finger are a number of longitudinal ribs D, slightly undercut, as shown at Fig. 4. The longitudinal ribs D may be applied to any or all of the glove fingers, but they are most 65 essential to the index finger. The thumb E of the glove will also be provided with a nail e in a normal position, but another nail e' may be added and located on the inner side of the glove thumb over the fleshy part 70 of the human thumb within, as shown at Fig. 3. For certain classes of work, the ribs, instead of being longitudinal, as shown at Fig. 2, may be placed transversely, as 75 shown at Fig. 3.

At Fig. 5 may be seen one mode of picking up a small object, which will be seen at f clutched between the nail C of the index finger and the inner nail e' of the thumb.

The glove fingers may be manufactured as 80 stalls which may be fitted over the fingers of old fashioned gloves, only as a temporary expedient.

Having now described my invention, I 85 claim:

In combination, an india rubber glove finger provided with an artificial nail and an india rubber glove thumb provided with an artificial nail adapted to register with the fleshy part of the thumb tip and to co-act 90 with the nail and said glove finger.

In testimony whereof I have signed my name to this specification in the presence of two subscribing witnesses.

HERBERT CECIL FINLAY.
